UNITED STATES PATENT OFFICE.

LÉON GAUMONT, OF PARIS, FRANCE.

PHOTOGRAPHIC OR CINEMATOGRAPHIC FILM.

1,159,924.

Specification of Letters Patent.

Patented Nov. 9, 1915.

Application filed July 8, 1914. Serial No. 850,530.

To all whom it may concern:

Be it known that I, LÉON GAUMONT, of Paris, France, have invented certain new and useful Improvements in Photographic or Cinematographic Films, of which the following is a specification.

For the manufacture of photographic and cinematographic films (known as non-inflammable or safety films), various combustible carriers have been employed. Some of these have had to be abandoned, in spite of their being much cheaper than films of celluloid or its derivatives, by reason of the fact that they increased considerably in dimensions in the developing and washing baths and lost all their strength.

I have conceived the idea of employing collodion as the vehicle for the sensitive material, in combination with such carriers as referred to above (viscose, for example), in place of the usual sensitized coating (usually gelatino bromid). The collodion does not alter or affect the carrier in being spread thereon, whereas gelatin coatings contain water, which affects certain carriers, such as viscose, when spread thereon.

An embodiment of the invention is illustrated in Figure 1 of the accompanying drawing, which figure illustrates a sensitized film in longitudinal section. Fig. 2 is a like view of another embodiment, and Fig. 3 is a like view of still another embodiment.

a represents a sheet or film of "viscose" or the like (the thickness of which is much exaggerated), and *b* a very thin layer of collodion (also much exaggerated) applied on one face of the layer *a*, the collodion layer being sensitized by well-known means.

As the layer or coating of sensitized collodion thus applied on the viscose is extremely thin, it permits of running the film very rapidly through the developing, fixing and washing baths and of performing these photographic operations in such a short period of time that the action of the water on the carrier (viscose for example) is reduced to the utmost possible extent. By this combination of an incombustible and cheap carrier, such as viscose, with a thin superficial coating of collodion, the drawback of viscose, viz: that of swelling and becoming distorted, is avoided, because the col-

lodion permits the photographic pictures to be produced, in such a short time that the moisture cannot attack the viscose in this time. Moreover, although the employment of collodion reduces to a minimum the period of contact with the water, the carrier can also be lightly impermeabilized by a superficial treatment. As shown in Fig. 2, the carrier *a* may have applied to each side thereof a layer of impermeable material *a'*, as for instance, a suitable varnish, as a varnish with a celluloid base, over one of which layers the sensitized collodion layer *b* is applied. Or, as illustrated in Fig. 3, the carrier *a* may have a layer of impermeable material *a'* on one side and a layer of the sensitized collodion *b* on the other. Under these conditions, the passage of the film through the baths above mentioned has no effect upon the carrier of viscose or similar material. It may also be remarked that the employment of the collodion forming a coating for the viscose carrier allows of obtaining pictures of much greater fineness and transparency than is generally obtained by gelatino bromid or gelatino chlorid.

Claims:

1. A film comprising a layer of a transparent, flexible incombustible carrier, and a very thin layer of sensitized collodion, allowing the developing, washing and fixing to be so rapidly effected that the film does not have time to be appreciably affected by the water present during treatment.

2. A film comprising a layer of viscose, and a very thin layer of sensitized collodion, allowing the developing, washing and fixing to be so rapidly effected that the film does not have time to be appreciably affected by the water present during treatment.

3. A film comprising a layer of a transparent, flexible incombustible carrier, and a very thin layer of sensitized collodion, allowing the developing, washing and fixing to be so rapidly effected that the film does not have time to be appreciably affected by the water present during treatment, said carrier having an impermeable coating.

4. A photograph film, comprising a transparent, flexible non-inflammable body or base, an impervious coating, and an outer sensitized collodion coating.

5. A photographic film, comprising a transparent, flexible non-inflammable body or base and a sensitized collodion coating.

6. A photographic film, comprising a transparent, flexible non-inflammable body or base, an impervious coating on one side, and an outer sensitized collodion coating on the other side.

In witness whereof, I have hereunto signed my name in the presence of two sub-¹⁰scribing witnesses.

LÉON GAUMONT.
